UNITED STATES PATENT OFFICE.

JNO. S. LEWIS, OF ATHOL, MASSACHUSETTS.

MODE OF CUTTING THE UPPERS OF BOOTS.

Specification of Letters Patent No. 13,852, dated November 27, 1855.

To all whom it may concern:

Be it known that I, JOHN S. LEWIS, of Athol, in the county of Worcester and State of Massachusetts, have invented a new and 5 useful Improvement in the Mode of Cutting the Uppers of Boots; and I do hereby declare that the following is a full, clear, and exact description of the same, reference being had to the accompanying drawings, 10 forming part of this specification, in which—

Figure 1, exhibits in black outline, tinted, the form into which the stock is cut according to my invention for the fronts of 15 boots, and also exhibits in red outline the common form of boot front, showing the saving effected by my plan. Fig. 2, exhibits in black outline a side view of a boot front cut on my plan, after it has been 20 crimped, and in red outline its difference from one cut on the old plan, in the same state. Fig. 3, is a side view of a complete boot "upper" made on my plan.

Similar letters of reference indicate 25 responding parts wherever they occur in the several figures.

My invention relates to the mode of cutting the fronts the principal advantage of which is the saving of stock. This mode 30 consists of cutting the front all the way down no wider or very little wider than the usual width of the part which is to form the front of the leg omitting the piece which is commonly left on each side of the front 35 to meet the lower part of the back or heel seat. The vacancy which this leaves after the front has been crimped and the back fitted to it may be filled in various ways.

By reference to the red outlines in Fig. 40 1, it will be understood that by cutting the backs in the common way a piece of leather of the width included between the lines *a*, *a*, and of the whole length of the boot front will be consumed for every front to form 45 the projecting corners *f*, *f*, in excess of the quantity consumed in cutting the fronts to the form indicated by *A*, *A*, in black outline, which is the form of the fronts cut on my plan. This wastes fully one fourth of 50 the best stock as it only allows three fronts

to be obtained from a piece of leather from which by my plan four may be obtained.

By reference to the black outline Fig. 2, it will be seen that when a front *A*, is folded and crimped there is a triangular vacancy *b*, 55 representing a piece wanting to complete the common form of the front. The methods of filling this vacancy are various. I consider the best method to be to cut a counter piece *C*, to cover the heel seat of the back 60 *B*, which would be cut of the common form, and to extend the said counter piece forward in the proper form to cover or fill the vacancy *b*, and this is represented at *g*, in Fig. 3. In this case the outside counter 65 piece *C*, serves as stiffening. Another method is to fit in a piece or gusset of leather india rubber cloth or other material to fill this vacancy serving the same to the heel seat or lower part of the back cut in 70 the common way, and to the oblique line *e*, forming part of the lower edge of the front. Another method is to cut the back with an extra piece on each side of the lower part 75 of proper form to fill the said vacancy, but this latter method will cause some waste in cutting the backs, though this waste is much less than what is made in the old plan of cutting the fronts, as the fronts are almost invariably cut from stock of much better 80 quality than the backs.

It should be observed in crimping the front cut on my plan, that it should be drawn the tightest at the two ends of the oblique line. In crimping the common front 85 it is always drawn the tightest about midway between these points or in a dotted line from the point *d*, to the nick *e*, which shortens the front about one inch more than my plan. As a medium front is about seven 90 inches wide, about seven square inches of leather is saved in this way by my plan, in addition to what is saved in the manner before described. In cutting out the fronts I should never cut them wider in any part 95 than is necessary to form the front of the leg, as in that way is the greatest economy, but I do not wish to confine myself strictly to this width as by cutting them somewhat wider at the part where the old front has 100

the corners f, f , produced, a saving of stock may still be effected.

What I claim as my invention and desire to secure by Letters Patent, is—

5 Cutting the boot front all the way down no wider or but little wider than the usual width of the part which is to form the front of the leg, and filling the vacancy b , which is thus caused when the front is crimped,

by a separate piece, by extending the back 10 or counter, or by a piece produced in any other way whereby the saving is effected in cutting the fronts substantially as herein described.

JOHN S. LEWIS.
